CLAIM

The ornamental design for a faucet handle, as shown and described.

DESCRIPTION

FIG. 1 is a perspective view of a faucet handle showing my new design;

FIG. 2 is a top plan view thereof;

FIG. 3 is a first side view thereof;

FIG. 4 is a first end view thereof;

FIG. 5 is a second end view thereof; and,

FIG. 6 is a bottom view thereof.

The broken line shown in FIG. 6 is included for the purpose of illustrating a portion of the faucet handle that forms no part of the claimed design.
